AMUSEMENT AND EXERCISING DEVICE

Laurence H. Bibus, Philadelphia, Pa.

Application November 1, 1937, Serial No. 172,079

11 Claims. (Cl. 273—102.3)

The present invention relates to an amusement device, and it relates more particularly to a prize-projecting amusement device operable in response to a thrown projectile.

5 An object of the present invention is to provide an amusement device which will hurl a prize to a player when the latter has succeeded in striking a target with a projectile.

Another object of the present invention is to 10 provide a projectile-responsive prize-projecting device which not only taxes a player's skill in throwing the projectile towards the target, but also taxes the player's skill in catching the resultant projected prize.

15 Another object of the present invention is to provide a comical target-bearing mechanized figure whose limbs will be set in motion to operate an independent prize-projecting device when said target has been struck.

20 With the above and other objects in view, which will appear more fully from the following detailed description and accompanying drawings, the present invention consists of a mechanized figure including a pivoted spring-tensioned limb, means for cocking said limb, a detent for holding said limb in a cocked position, and a detent-release controlled by a target, whereby a projectile striking said target will release the detent and thus permit the pivoted spring-tensioned 25 limb to forcibly swing through space, and a separate prize-projecting device removed from said mechanized figure and including a prize-bearing spring-board positioned in proximity to the path of said pivoted limb, a detent for holding said spring-board in a flexed condition, and a detent-release or trip-arm means operable generally simultaneously with said limb detent-release, whereby a prize will be forcibly projected by said spring-board when the target has been struck by a projectile, creating the illusion that the 30 swinging limb has encountered and projected the prize.

For the purpose of illustrating the invention, there is shown in the accompanying drawings, forms thereof which are at present preferred, 45 since the same have been found in practice to give satisfactory and reliable results, although it is to be understood that the various instrumentalities of which the invention consists can be variously arranged and organized and that the invention is not limited to the precise arrangement and organization of the instrumentalities 50 as herein shown and described.

In the accompanying drawings, in which like 55 reference characters indicate like parts:

Figure 1 represents a side elevational view of one embodiment of the present invention illustrating a mechanized figure operatively disposed relative to a separate prize-projecting device, with parts of said figure broken away to expose to view the interior thereof.

Figure 2 represents an enlarged sectional view taken on line 2—2 of Figure 1, looking in the direction of the arrows.

Figure 3 represents a fragmentary sectional view taken on line 3—3 of Figure 2, looking in the direction of the arrows.

Figure 4 represents an enlarged fragmentary perspective view of the limb-cocking, limb-detent, and detent-release mechanism disposed within the figure illustrated in Figure 1.

Figure 5 represents a front elevational view of the prize-projecting device illustrated in Figure 1.

Figure 6 represents a plan view of the prize-projecting device illustrated in Figure 1.

Figure 7 represents an enlarged fragmentary rear perspective view of the prize-projecting device illustrated in Figures 1, 5 and 6.

Figure 8 represents a fragmentary rear perspective view of a modified form of prize-projecting device adapted to successively project a series of individual prizes without interruption.

In the particular embodiment of the present invention herein shown for the purpose of illustration or exemplification, a mechanized hollow figure of a jackass 9 is stationarily supported relative to the ground in any suitable manner, as for instance, by means of the rigid figure-supporting shaft 10 housed within a foreleg 11 and having its lower shaft extremity firmly secured to a base 12 by being welded or bolted thereto. An even firmer support may be obtained by providing a pair of figure-supporting shafts 10, 10 each respectively disposed within the two spaced figure forelegs 11, 11.

The hind legs 13, 13 of the jackass are preferably pivotally related to the hindmost portion of the body by means of the pivot shaft 14, and the hooves 15, 15 of these hind legs are thus constrained to describe the arc 16 through space 45 when the hind legs are being cocked and also when these hind legs are subsequently released to simulate a kicking action under the contracting influence of a tensioned helical spring.

The pivot shaft 14 may be journaled within 50 suitable apertures 17, 17 in the hindmost body portion, and the two shaft extremities 18, 18, preferably project through these apertures 17, 17 and into the top hollow part of the hind legs 13, 13. These hind legs may be keyed to the 55

5 pivot shaft extremities 18, 18 by any suitable means, such as by mating polygonal apertures 19, 19, disposed in the inner walls of these hind legs, with the shaft extremities 18, 18 of similar polygonal cross-section. These hind legs 13, 13 may be permanently secured to the shaft extremities by any suitable means, such as the lock nut and washer assemblies 20, 20 or the like.

10 A yoke 21 is preferably formed integrally with said pivot shaft 14, and is adapted, together with said shaft, to rotate to a limited degree within the hindmost portion of the body 9.

15 The hind legs 13, 13 may be forcibly swung through space in realistic simulation of a kicking action, under the contracting influence of a pair of tensioned helical springs 22, 22 disposed within the body 9. These springs may be anchored to the stationary body cross-bar 23 at their front ends, and to the movable yoke cross-

20 arm 24 at their opposite rear ends, by means of the spaced anchoring-collars 25, 25 or the like. The yoke cross-arm 24 may be notched at its midpoint 26 to receive a spring-pressed detent 27 which engages said notch when the hind legs have been cocked or raised to their initial kicking position. This detent 27 is preferably pivotally related to a detent housing 28 mounted within the hindmost portion of the body 9, at the fulcrum point 29, and the detent 27 is normally urged

25 into the cross-arm notch 26 under the influence of a small helical compression spring 30 stationarily related to the body 9 through said detent housing 28.

30 A target bell or gong 31 is preferably mounted on the rear of the jackass body 9, and may be fixedly secured thereto by a hollow sleeve 32 imbedded within the hindmost portion of the body 9. A detent release mechanism may be operatively mounted within said sleeve 32 and may consist of the plunger 33 slidably mounted within said bell supporting sleeve 32 and having a target-forming head 34 projecting exteriorly and rearwardly of said bell 31, and having its opposite end 35 in close proximity to, and operatively aligned with, the downwardly depending detent-arm 36.

35 A downwardly extending cocking arm 37 is preferably centrally secured to the pivot shaft 14, and the lower extremity of this cocking arm 50 may be straddled in unhindered relation by a cocking-yoke 38 supported at its free end by a leaf spring 39 mounted on the detent housing 28, and supported at its other end by the cable 40. This cable 40 may be operatively extended to a 55 foot-operated cocking-treadle 42, which is preferably disposed at some remote point, by means of suitable sheaves or pulleys 41, 41 or the like.

60 In operation, a player stationed at some distance away from the hereinabove described mechanized figure (which we will assume has been cocked), attempts to strike the target head 34 with a projectile. If his aim is imperfect, he may succeed in merely striking the bell 31 which will then be sounded thereby. If his aim is good, the projectile, traveling in the direction of the arrow 43, will strike the target head 34 and slide the plunger 33 in the direction of said arrow 43, thus causing the inner plunger end 35 to contact and slightly pivot the detent arm 36 about the fulcrum 29 against the action of the compression spring 30. The detent 27 will thus be tilted upwardly, and lifted out of the yoke-notch 26, whereupon the tensioned helical springs 22, 22 will rapidly contract and cause the yoke 21 together with its associated pivot shaft 14 to par-

5 tially rotate. The extent of this rotation may be limited by the cocking arm 37 coming into contact with the fixed end of the flat leaf spring 39, or it may be limited by separate stop means. This rotary movement of the pivot shaft 14 is transmitted to the hind legs 13, 13 which then simulate the kicking action hereinabove referred to, and the hind leg hooves 15, 15 describe an arc 16 through space.

10 The operator of this amusement device may 10 then recock the hind legs 13, 13, that is, he may raise these hind legs to the elevated or kick-starting position illustrated in Figures 1 and 3, by depressing foot pedal 42. This serves to draw the yoke end of the cable 40 forward in the direction 15 of the arrow 44 and the resulting forward movement of the cocking-yoke 38 carries forward with it the cocking arm 37; the contracted helical springs 22, 22 being extended and tensioned simultaneously therewith. When the detent 27 enters the notch 26 centrally provided in the yoke arm 24, the hind legs 13, 13 are fully cocked, and the foot treadle 42 may then be released. The flat leaf spring 39, which had been flexed during this cocking operation is then permitted to resume its normal position illustrated in Figures 1, 3 and 4, and in so doing, positions both itself and its associated yoke 38 in non-obstructing relation 20 to the cocking arm 37.

25 If desired, auxiliary figure movements and 30 sound effects may accompany the hereinabove described kicking operation. Thus, the head and neck portions 45 of the jackass may be caused to oscillate to and fro when the target has been struck, by pivotally securing this portion 45 to 35 the body 9 at the pivot point 46, and then imparting an oscillatory movement to the neck through the rotating crank arm 47 and connecting rod 48. The crank arm 47 may derive its rotary movement from any suitable electric motor 49 40 through a chain-driven reduction gear unit 50. If desired, the electric motor 49 may be operated only when the target head 34 has been struck by a projectile and the hind legs 13, 13 are being 45 swung through space, or the motor 49 may be operated whenever these legs are in the uncocked position, but in either case the motor operation is preferably controlled by electrical contacts whose juxtaposition is determined by the physical position of the figure legs. 50

55 Thus also, a vacuum horn 51 may be operated by an air-pump 52 connected to a leg 53 of the yoke 21 by the connecting rod 54 and the end link 55. The noise emitted by the horn which will accompany each kick effected by the hereinabove 55 described mechanized figure, may resemble the braying of a jackass.

60 According to the present invention, a separate prize projecting device 56, one form of which is indicated generally in Figures 1, 5, 6 and 7 and 60 which is shown in modified form in Figure 8, may be operatively positioned relative to the hereinabove described mechanized figure, and may be so controlled by, or timed relative to, the legs thereof (the hind legs 13, 13 of the particular 65 embodiment illustrated in the drawings), as to hurl the prize to the player whenever the limbs have been set in motion due to the target having been hit. Thus, the present invention not only provides means for testing a player's skill in aiming a projectile at a target and for indicating and rewarding him for his success in so doing, but the present invention may also test the player's skill in catching the projected prize hurled to him. 70

The prize-projecting device 56 may include a compression spring or a spring-board 57 formed from a steel leaf spring or the like, having a compartment 58 attached thereto within which a prize may be placed and temporarily retained until forcibly thrown out into space in the direction of arrow 70 by the unflexing of the compression spring, or of the spring board 57. This spring board may be suitably secured at its fixed end to an anchor-block 59 mounted on the inclined base board 60, and may be provided with the series of horizontal prize-bearing shelves 62, 62 indicated in Figures 1, 5 and 6.

A detent-receiving aperture 63 is preferably disposed in the free end of the spring-board 57 and is adapted to meet and receive the detent 64 when said spring-board 57 has been flexed backwardly. The detent 64 is preferably rigidly mounted on a rotatable detent-bearing bar 65 having its rounded ends journaled between the bearing blocks 66, 66 mounted on the upright frame members 61, 61. The detent 64 may be provided with an overhanging lip 67 which slides over and contacts that portion of the spring-board surface immediately adjacent the aperture 63 in response to the forces exerted by a pair of flat leaf springs 68, 68 on the detent 64, through the detent-bearing bar 65. The pivoted detent-bearing bar 65 is preferably provided with projections 69, 69 disposed somewhere within the path of the arc 16 described by the hoof-extremities 15, 15 on the swinging hind legs 13, 13 of the mechanized jackass.

In operation these swinging hooves 15, 15 encounter the underside of the projections 69, 69 and cause the detent-bearing bar 65 to rotate slightly in opposition to the forces exerted by the leaf spring 68, 68, thus tilting the detent-lip 67 into an inoperative position. The spring-board 57 is released thereby and immediately unflexes, hurling out into space in the direction of the arrow 70, the prize which had been placed within the springboard compartment 58. Due to the rapidity of the action, and the instantaneous proximity of the hooves and the prize, an impression is created that the jackass itself directly kicks the prize to the player.

A modified embodiment of this prize-projecting device and one which is adapted to hurl a series of individual prizes in operative succession without interruption for reloading each time a prize has been projected, has been illustrated in Figure 8.

In this modified embodiment, a multiplicity of spring-boards 57, 57 may be provided and each of these spring-boards may have associated therewith an individual detent 71. These detents are preferably individually pivotally mounted between the detent-confining blocks 72, 72 by means of the detent pivot shafts 73, 73. These detents may each be urged into the spring-board locking position by a helical tension coil 71a. A rotatable shaft 75 may be journaled between the bearing blocks 66, 66 mounted on the upright frame members 61, 61 and this shaft 75 may be provided with a series of detent-releases each comprising a collar 76 rigidly secured to the shaft 75, and a detent-release 77 projecting radially therefrom. These detent releases 71, 77 are radially staggered relative to each other and are each adapted to successively enter between their respective juxtaposed detent-confining blocks 72, 72 and rotate the enclosed pivoted detent 71 against the action of the helical tension spring 73 by an amount sufficient to release the free

end of the spring-board 57. Thus, the shaft 75 may be rotated in stages. The number of these stages required to rotate this bar one complete revolution is dependent upon the number of prizes which may be projected by the device without requiring reloading any of the spring-boards, or in other words, upon the number of spring boards. The bar 75 may be rotated by means of the pair of ratchet wheels 78, 78 mounted on either end of said bar, and the operatively juxtaposed pawls 79, 79. The ratchet wheels 78, 78 are peripherally divided into a series of stages, the number of stages being equal to the number of spring-boards. The pawls 79, 79 are each mounted upon hoof-intercepting blocks 80, 80 pivotally related to the framework 61 of the prize projecting device at the pivot points 81, 81. The upward movement of the free ends of these pivoted blocks 80, 80 may be limited by the U shaped stops 82, 82 fixedly secured to the framework.

In operation the swinging hooves 15, 15 simultaneously contact of the blocks 78, 78 and elevate the free ends thereof by an amount limited by the height of the U shaped stops 82, 82. The flexible pawls 79, 79 are raised thereby, partially rotating the ratchet wheels 78, 78 and the associated bar 75. This rotary movement is transmitted through the collars 76, 76 to the projecting detent-releases 71, 77, the extremities of which are adapted to enter between the detent confining blocks 72, 72 and singly pivotally rotate the detents 71, 71 by the slight amount necessary to release the spring boards 57, 57.

As may be readily seen, these spring boards 57 need not be reloaded each time a prize has been projected, but on the contrary a plurality of prizes, the number of which is dependent upon the number of spring boards provided, may be successively projected without interrupting the operation of the prize projecting device.

While the prize projecting devices illustrated in Figures 1 and 5 to 8, inclusive have been illustrated and described in operative juxtaposition to the hereinabove described mechanized figure, it is to be understood that the target 34 need not be mounted upon a separate figure but instead this target may be mounted either directly on the prize projecting devices illustrated in the drawings, or elsewhere, and may directly control the spring board detent 64 or 71. Thus, the projecting blocks 69 or 80 need not be operated by a separate mechanized figure, but indeed these blocks might with suitable modification serve as the target itself. One target may independently control the spring board detent 64 or 71. Thus, the projecting blocks 69 or 80 need not be operated by a separate mechanized figure, but indeed these blocks might with suitable modification serve as the target itself. One target may independently control both the mechanized figure and the prize projecting device. Thus, the prize projecting device may be so timed relative to the moving hooves as to independently project a prize at the hooves nearest approach thereto. The illusion that the jackass itself kicks the prize out may thus be effected.

It is to be expressly understood that the present invention is not limited to the particular figure illustrated and described, but on the contrary any figure (human, animal or comic strip) may be readily substituted therefor, and either arms or legs, or both, may be swung to set into operation the prize-projecting device.

Moreover, the mechanized figure and prize projecting device both may be air-motivated and, if desired, the target may electrically control the movements of these devices instead of mechanically controlling their operation.

The present invention may be embodied in

other specific forms without departing from the spirit or essential attributes thereof, and it is therefore desired that the present embodiment be considered in all respects as illustrative and not restrictive, reference being had to the appended claims rather than to the foregoing description to indicate the scope of the invention.

Having thus described the invention, what is hereby claimed as new and desired to be secured 10 by Letters Patent, is:

1. A skill-rewarding amusement device for testing a player's throwing and catching skill, including a target-controlled figure having a movable limb movable in a direction towards the player, means responsive to the impact of a player-directed object on said target for rapidly moving said limb in said direction, and movable catapult means separate from said limb arranged temporarily to hold a prize at rest in spaced relation from said limb and near the path of movement thereof, said catapult means being further arranged to catapult said prize towards the player when said target has been struck, whereby said prize will appear to have been projected directly by said limb.

2. A skill-rewarding amusement device for testing a player's throwing and catching skill, including a figure having at least one pivotally pivoted spring-tensioned limb movable, when released, in a direction towards the player, limb-cocking means operable at a point removed from said figure, a limb-detent for releasably securing said spring-tensioned limb in a cocked position, projectile-responsive means for releasing said limb-detent, and movable catapult means separate from said limb arranged temporarily to support a prize motionlessly in proximity to the path of movement of said limb, said catapult means being further arranged to catapult said prize towards the player when said target has been struck, whereby a well-aimed projectile encountering said target will cause said limb to swing through space and apparently directly project a prize towards the player.

3. A skill-rewarding amusement device for testing a player's throwing and catching skill, including a figure having at least one pivotally pivoted spring-tensioned limb movable in a direction towards the player, limb-cocking means, a limb detent for releasably securing said spring-tensioned limb in a cocked position, a projectile responsive limb-detent release, and movable catapult means separate from said limb arranged temporarily to support a prize motionlessly in proximity to the path of movement of said limb, said catapult means being further arranged to catapult said prize towards the player when said target has been struck, whereby a properly-directed projectile will operate said limb-detent release causing said pivotally pivoted limb to swing through space and apparently directly project a prize towards the player.

4. A skill-rewarding amusement device including a mechanized animal figure having a relatively stationary body, a rear leg pivotally secured to said body and arranged to be swung outwardly and rearwardly in simulation of a kick, an external target mounted at the rear end of said body, a projectile-responsive plunger centrally disposed on said target and arranged, when struck, to set into motion said rear leg, and prize-projecting means disposed near the path of movement of said rear leg and arranged to catapult a prize towards the player when said target has

been struck, whereby said prize will appear to have been projected by said rear leg.

5. A skill-rewarding amusement device including a target-bearing figure having a movable limb movable in a direction towards the player, means responsive to the impact of a projectile on said target for rapidly moving said limb in said direction, and spring-actuated means controlled by said movable limb for catapulting a prize towards the player, said means including a prize-supporting member for fixedly holding said prize near the path of movement of said limb, a detent for releasably securing said prize-supporting member against the action of said actuating spring, and detent-release means for rendering said detent inoperative, said latter means being at least partly disposed within the path of movement of said limb, whereby the supported prize will seemingly be catapulted to the player by said limb when said target has been struck. 20

6. A skill-rewarding amusement device including a target-controlled figure having a movable limb movable in a direction towards the player, means responsive to the impact of a player-directed object on said target for rapidly moving 25 said limb in said direction, and prize-projecting means adapted fixedly to support a prize near the path of movement of the extremity of said limb, said prize-projecting means being arranged to catapult said prize towards the player when 30 said target has been struck and said limb set into motion, whereby said prize will appear to have been projected by the rapidly moving extremity of said limb.

7. A target-controlled figure having a cockable limb, arranged, when cocked, to be set into motion by the striking of said target, said limb having a portion fixedly related thereto adapted to receive the thrust of limb-cocking means, remotely operable limb-cocking means movable from an inoperative position out of contact with said portion into driving engagement therewith, to cock said limb, and means urging said limb-cocking means out of driving engagement with said portion, and clear of the path described by said portion, when said limb has been cocked. 40 45 49

portion, which said limb has been cocked.

8. An amusement apparatus comprising a mechanized animal figure including a stationary foreleg and body, said figure being supported through said foreleg, a spring-tensioned rear leg pivotally mounted on said body and adapted to be swung outwardly through space under the influence of said spring in simulation of a kick, said rear leg being permanently flexed, a detent mounted within said body for releasably securing said rear leg in a cocked position, and an external target mounted on the rear of said body, said target being provided with a centrally disposed projectile-responsive plunger adapted, when struck by a projectile, to render said rear leg detent inoperative.

9. An amusement apparatus comprising a mechanized animal figure including a stationary foreleg and body, said figure being supported through said foreleg, a spring-tensioned rear leg pivotally mounted on said body and adapted to be swung outwardly through space under the influence of said spring in simulation of a kick, a 65
detent mounted within said body for releasably securing said rear leg in a cocked position, an external target mounted on the rear of said body, 70
said target being provided with a centrally disposed projectile-responsive plunger adapted, when struck by a projectile, to render said rear leg detent inoperative, and cocking-means, operable at a point remote from said mechanized figure. 75

for returning said rear leg to a cocked position, said cocking-means being provided with automatic means for returning the same to its original position prior to subsequent movement of said rear leg.

10. A target-controlled prize-projecting device for forcibly projecting a separate prize each time the target has been struck by a projectile, said device being adapted, after a single loading operation, to uninterruptedly project a predetermined number of separate prizes, comprising a plurality of spring-actuated prize-supporting members each adapted to temporarily support a separate prize, an individual detent operatively associated with each of said prize-supporting members for releasably securing each of said prize-supporting members against the action of their respective actuating springs, an individual projectile-responsive detent release operatively associated with each of said individual detents, said detent releases each being adapted to successively render their respective detents inopera-

tive, and common means interposed between said target and each of said detent releases adapted to operate the latter each time said target has been struck, thereby permitting each of said actuating springs to successively unflex and forcibly project a prize from their respective associated prize-supporting members.

11. A skill-rewarding amusement device including an animal figure having a generally stationary body, a limb pivotally secured to said body and arranged to be swung outwardly, a target on said body arranged when struck suddenly to set said limb into motion, and prize-projecting means arranged to catapult a prize through space towards the player along a path generally the same as that which the prize would have described had it been struck directly by the end of said moving limb, said prize-projecting means being operatively synchronized with said target, whereby said prize will appear to have been projected by said limb.

LAURENCE H. BIBUS.
